UNITED STATES PATENT OFFICE.

MATTHIAS BROCK, DECEASED, LATE OF BOSTON, MASSACHUSETTS, BY EDWARD L. BROCK, ADMINISTRATOR, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR PRESSING THE SOLES OF SHOES.

1,399,742.

Specification of Letters Patent. Patented Dec. 13, 1921.

Application filed February 8, 1919. Serial No. 275,786.

To all whom it may concern:

Be it known that MATTHIAS BROCK, deceased, late of Boston, in the county of Suffolk and State of Massachusetts, invented certain Improvements in Machines for Pressing the Soles of Shoes, of which the following description, in connection with the accompanying drawings, is a specification, like reference characters on the drawings indicating like parts in the several figures.

In sole-laying machines and in sole-leve-
eling machines, both of which are used in
the manufacture of shoes, it is desirable to
brace or sustain the "extension" of the
shoe during the application of pressure to
the bottom of the sole. In machines of both
the said classes such bracing or sustaining
is intended to avoid bending the extension
over the edge of the last. There is, how-
ever, an additional consideration for such
sustaining in the case of sole-laying when
the shoe extension includes some shoe ele-
ment in addition to the tread sole. Inci-
dently to sole-laying the tread sole is se-
cured temporarily by cement, and when
there is an extension element to be united
with the margin of the tread sole it is cus-
tomary to form the union, in the beginning,
by cement. But if the cement union is not
uniform and close throughout the margin of
the extension a crack will appear and there-
by detract from the appearance of the fin-
ished product. In order, therefore, to in-
sure a close and uniform cement union the
extension must be sustained against the bot-
tom pressure.

In view of the foregoing considerations
the present invention provides improved
means for sustaining the extension of a shoe
against the bottom pressure, said means be-
ing applicable to a sole-laying machine to
sustain the extension against the sole-laying
pressure, or to a sole-leve-
eling machine to
sustain the extension against the sole-leve-
eling pressure.

In operating upon shoes of the Goodyear-
welt type the sustaining means would bear
on the welt-strip, while in operating upon
shoes of other types it would bear on the
shoe element that occupies the position cor-
responding to that of a welt-strip. For
convenience of expression, therefore, and

without implying any limiting significance
other than that of location, such terms as 55
"welt" and "welt portion" are used in their
broadest sense in the following description
and claims.

More specifically an object of the present
invention is to equalize the pressure upon
the extension at each side of the shoe rela-
tively to that at the opposite side, and this
object is attained by a structure that acts
automatically to equalize the pressure even
to the extent of accommodating itself to lasts
that have various angles of transverse in-
clination. Thus, if the last happens to be
canted by reason of a peculiar formation or
by reason of an inaccuracy in the angle of
the last-pin-socket, the means by which the
extension is pressed will make due compen-
sation for such peculiar formation or inac-
curacy and still insure equalization of pres-
sure at the two sides of the shoe. It is
thought that this is the first instance in 75
which pressure-applying means, whether it
be a part of a sole-laying machine or a part
of a sole-leve-
eling machine, has been con-
structed and arranged to equalize the pres-
sure on the extension at each side of the 80
shoe relatively to that at the other side, and
claims of correspondingly broad scope are
sought.

Another object of the invention is to pro-
vide a welt-sustaining platen having a con-
tinuous welt-engaging surface formed and
arranged to extend from a point behind the
ball-portion on one side of the shoe to and
around the toe-end and thence to a point
behind the ball-portion at the opposite side, 90
so that there will not be any gap or break in
the effective surface of the platen.

Still another object of the invention is to
provide a platen capable of lengthwise ad-
justment for shoes of various sizes without
forming any gap or break in its welt-en-
gaging portion by reason of being adjusted.
In addition to the capacity for lengthwise
adjustment the invention has for another ob-
ject provisions for permitting sidewise ad-
justment, to the end that it may be used upon
shoes of different widths in addition to
shoes of different lengths.

Other objects of the invention are to pro-
vide improved means for varying the effec-
tive size of the platen, means for determin-

ing the initial position of the platen with regard to its angle, and other improvements that will be described in due course.

Of the accompanying drawings, which 5 illustrate a preferred embodiment of the invention as applied to a sole-laying machine of otherwise well known construction,—

Figure 1 represents a side elevation, partly broken away, including last-sustaining 10 means, pressure-applying means, and welt-sustaining means mounted in co-operative relation to a shoe;

Fig. 2 represents a top plan view of an adjustable platen which embodies features of 15 the present invention;

Fig. 3 represents a top plan view of an improved holder by which the platen may be supported, and by which it may be opened manually for the insertion and removal of 20 a shoe;

Fig. 4 represents an end view of an oscillatory mounting by which the holder and platen may be supported to enable the platen to move automatically with pressure-equalizing effect;

Fig. 5 represents a sectional view through the ball-bearing structure intersected by line A—A of Fig. 4;

Fig. 6 represents a cross-section through 30 a jointed portion of the platen in the plane indicated by line X—X of Fig. 2;

Fig. 7 represents a cross-section through that portion of the platen intersected by line B—B of Fig. 2;

Fig. 8 represents an end view similar to Fig. 4 but includes means for making a preliminary adjustment, and includes portions of the platen together with a conventional representation of a shoe, to indicate the coincident relation of the effective plane of the platen and the axis about which the platen rocks to execute its equalizing motion; and

Fig. 9 represents an underneath perspective of a fragment of the platen assemblage.

Referring to Fig. 1, which illustrates a portion of a sole-laying machine of the same general character as that disclosed in Letters Patent of the United States No. 1,066,473, granted July 8, 1913, on applica-

tion of H. A. Davenport, the upper head is indicated at 10, and one of the two rods to which it is clamped is indicated at 12. This head is provided with a flange plate 14 to support the last-pin-holder 16 and to sup-

port the toe-rest 18. The last-pin 20 is pivotally connected to holder 16 by a pivot pin 22, and is constantly under the stress of a spring 24 that is effective to maintain the toe portion of the shoe in contact with the

60 toe-rest. In the present instance the toe-rest is in the form of a roller and is rotatably mounted in a fork structure at the lower end of an adjustable post 26. This post extends through a bore in a supporting block 28, and is supported adjustably in said block

by a nut 30. The block 28 is arranged to slide horizontally on the supporting flange 14 of the head, and is provided with an eccentric clamping member 32 arranged to contact with the bottom face of the flange to hold the block against movement. The eccentric member is provided with an operating handle 34 by which it may be tightened and released.

The pressure-applying means, which is 75 illustrated in a form embodying well-known construction, comprises a pad-carrier 36 in which are mounted a plurality of relatively movable pad-supporting sections 38. These sections are connected in pairs by oscillatory 80 pressure-equalizing members 40, which members are, in turn, connected by equalizing members such as that indicated at 42. Pivot pins 44 connect the sections 38 with the members 40, pivot pins 46 connect the 85 members 40 with the members 42, and pivot member 48 connects the members 42 with a foundation block 50. This block is mounted upon and sustained by compression springs 52, the latter resting upon the bottom of the 90 carrier 36.

So far as the fundamental principles of the invention are concerned, it does not matter whether the pressure-applying means is moved relatively to the last-sustaining 95 means or vice versa, but in the machine illustrated by said patent the last-sustaining means remains stationary and the carrier 36 is moved toward and from it by suitable power-driven mechanism. The carrier 36 as 100 a whole is supported by and adapted to rock on trunnions such as that indicated at 54, to enable it to assume an angle corresponding to the general longitudinal inclination of the bottom of the shoe, the oscillatory motion of the carrier about its trunnions being independent of the bodily movement toward and from the shoe. The relatively movable sections 38 support a sole-laying pad 56 which may be of any convenient or preferred construction.

The structure thus far described is not essentially different from that shown in the aforesaid patent, excepting that the toe-rest is adjustable to vary the longitudinal inclination of the shoe. For the purpose of sustaining the welt portion of the shoe independently of the support afforded by the last a the present invention provides a welt-sustaining platen adapted to bear on the welt continuously from a point behind the ball at one side of the shoe, thence along the forepart at one side of the shoe, around the toe end, and along the forepart at the opposite side to a point behind the ball portion. The structure of the platen is illustrated by Figs. 2, 6, 7, 8 and 9. Referring now to Fig. 2, the platen comprises welt-engaging sections 60, 60 connected by a hinge-member 62, and welt-engaging sec- 130

tions 64, 64 that form adjustable extensions of the sections 60, 60 respectively. The joints between the sections 60 and 64 are formed by tongues 66, grooves 68, screw studs 70, and slots 72. The tongues are formed on the members 60, and they fit into the grooves 68 in the members 64 as shown by Fig. 6. The slots 72 are formed in the members 60, and the studs 70 extend through the slots and are anchored in the members 64. These connections are arranged to afford longitudinal movement of the sections 64 relatively to the sections 60, and while various forms of holding devices would be capable of holding the sections in the desired relation, a preferred form of holding device is that shown by Fig. 6. This device comprises a compression spring 74 surrounding the stud 70, and a washer 76 interposed between the spring and the section 60. The friction of the parts due to the applied force of the spring is sufficient to hold the sections in the desired relation, but the holding effect is not so great as to prevent the sections 64 from being adjusted manually. Figs. 1 and 2 show a convenient form of device for adjusting the sections 64. This device comprises a cross bar 78 and a knob or handle 80 affixed thereto midway between its ends. The end portions of the bar are provided with slots 82 extending longitudinally, and these slots are occupied by pins 84 set in the sections 64 respectively. Oscillatory motion of the knob 80 about its axis will shorten the effective length of the platen on one side and increase the effective length on the other side simultaneously, while a bodily movement of the knob longitudinally of the platen will increase or diminish the effective length of the platen on both sides simultaneously. The slots 82 permit the necessary freedom of movement of the pins 84 required by the converging relation of the platen sections and by the angular movement of the cross bar.

In order to maintain continuity of bearing surface of the platen, notwithstanding the lengthwise adjustments, the sections 60, 60 are provided with welt-engaging surfaces 61 that are flush in relation to the welt-engaging surfaces 63 of the sections 64. The members 60 are tapered to chisel-edges 65 where their internal curvature merges into the straight portions of the members 64, 64 and this relation of the sections is what enables the platen to be adjusted for different lengths without interrupting the continuity of the effective welt-sustaining surface as a whole. The welt-sustaining structure afforded by the sections 60 and 64 jointly is illustrated by Fig. 6, the plane of which is near the point where the section 60 is reduced to a chisel-edge. In like manner the contiguous portions of the sections 60 are mortised one into another to provide

a flush hinge-joint that maintains the continuity of the platen regardless of opening and closing movement about the hinge member 62.

The platen is supported by a holder by 70 which it may be opened to receive and release the shoe, and closed to operative position relatively to the shoe. A holder for this purpose is shown separately by Fig. 3, and is included in Figs. 1 and 4. This 75 holder comprises a pair of bars 86, 86 connected to each other by a tubular hinge member 88 and having handle portions 90. The hinge member 62 that connects the platen sections 60, 60 extends through the 80 tubular hinge member 88 and is adapted to slide endwise in the latter. The members 86 are provided with holes 92 to receive pins 94 and 96. The pins 94 have heads 98 at their lower ends, said heads being arranged 85 to bear on the upper surface of the platen sections. The pins 96 are provided with heads 100 at their lower ends, said heads being arranged in undercut grooves 102 formed in the platen sections 64 (see Figs. 90 2 and 7). The pins 94 and 96 are free to slide in the holes 92 as the center pin 62 slides in the tubular member 88. The pins 62 and 96 are provided with collars 104 to prevent them from becoming separated 95 from the holder. Compression springs 106 are arranged upon the pins 62, 94 and 96 and are interposed between the platen and the holder to afford yielding backing for the platen. The connection afforded by the 100 pins 96 serves to transmit opening and closing movement of the holder sections to the platen sections, and at the same time permits the longitudinal adjustment of the platen sections 64 by which the effective 105 length of the platen is varied. The heads 98 of the pins 94 merely rest on the platen and afford the desired backing for the latter without interfering with the longitudinal adjustment or other relative motions. Tension springs 108 are connected to ears 110 of the holder sections in such manner as normally to swing the platen sections 64 toward each other. The handle portions 90 are so disposed that they may both be 115 grasped at the same time by one hand and moved toward each other to open the platen against the tension of the springs 108.

The platen holder is mounted in an oscillatory support comprising segmental members 112, and is connected to one of the latter by the hinge member 88 and to the other by screw studs 114. These studs extend through segmental slots 116 formed in the holder sections in concentric relation to the 120 hinge member 88. The studs 114, therefore, serve to limit the opening and closing movement of the holder sections.

The supporting members 112 are mounted in a stationary support 118 and are free to

oscillate in unison relatively to the latter to equalize the welt-sustaining effect of the platen at one side of the shoe relatively to that at the opposite side. For this reason the connection between the members 112 and 118 preferably includes ball-bearings so that the platen may accommodate itself without appreciable friction to various planes according to the transverse inclination of the welt-portion. Fig. 5 shows the mounting as comprising two series of anti-friction balls 120 interposed between the members 112 and 118. This assemblage is maintained in co-operative relation by segmental strips 122 and screws 124. The stationary supporting member 118 is provided with a dovetail portion 126 that fits in a correspondingly formed groove in a block 128 (see Figs. 1 and 8). This block is split through a portion of its length to provide two co-operative clamping sections, as shown by Fig. 8, and a clamping screw 130 is provided to draw them together to clamp the dovetail portion 126. The supporting member 118 is, therefore, capable of being adjusted longitudinally when the clamping screw 130 is loosened. The clamping screw is provided with an operating handle 132. The member 128 is connected to the supporting block 28 by a hinge pin 130, said pin being arranged to afford angular movement of the platen so that the latter may be adjusted according to the spring of the last. In order to adjust the member 128 for this purpose, ears 134 are formed thereon to receive between them a link 136. The lower end of the link is connected to these ears by a pivot pin 138, and the upper end is connected by a pivot pin 140 to a block 142. This block and a companion block 144 are provided with a series of serrations 146 to lock them together. A clamping screw 148 extends loosely through the block 142 and is provided with a head 150 arranged in an undercut groove 152 in the block 144. A wing nut 154 co-acts with the screw to hold the blocks in interlocked relation. When the nut is loosened, the screw 148, together with the block 142, is free to move up and down relatively to the block 144, the latter being provided with a slot to permit such movement of the screw. The block 144 is fixed to block 28.

The operation of a machine equipped with the welt-sustaining means hereinbefore described is substantially as follows: The pressure-applying carrier 36 stands initially in its lower position, leaving sufficient space for the manipulation of the lasted shoe. A shoe with its last is placed in position first by inserting the last pin 20 in the socket of the last, and then placing the toe portion of the shoe against the toe rest 18. While inserting the last pin in the socket of the last, the pin will preferably be tilted toward the left so that the toe end of the shoe will be pointed

downwardly. Then, before moving the forepart of the shoe upwardly to the toe-rest the operative will grasp and squeeze the handle portions 90 to open the platen so that the forepart of the shoe may move to the toe-rest without being unduly obstructed by the platen. When the shoe has been positioned against the toe rest the operative will release the handles 90 and the springs 108 will close the platen against the shoe, as shown by Fig. 8, with the platen overlying the welt portions x' , x' . If the toe portion of the shoe should happen to be too high or too low the error may be corrected by turning the nut 30 to depress or to raise the toe-rest, and the welt portions may thereby be adjusted to the same longitudinal inclination as the platen. If the effective length of the platen is too great or too small the operative will make the necessary adjustment by oscillating the knob 80 or by moving it bodily, as occasion may require. This will adjust the ball portions of the platen to conform to the corresponding portions of the shoe. While these adjustments are being made the platen will automatically assume an angle corresponding to the transverse inclination of the welt portion. This will involve rocking of the segmental support 112 on its ball-bearings to equalize the welt-sustaining effect at one side of the shoe relatively to that at the opposite side. This equalizing motion does not involve any appreciable transverse motion of the platen because the axis of oscillation, indicated at b in Fig. 8, is substantially coincident with the mean plane of the work-engaging surface of the platen.

When the welt-sustaining means has been adjusted to conform to the shoe, the operative will set in motion the mechanism by which the carrier 36 is lifted to apply the sole-laying pressure. When the carrier is at the upper limit of its traverse the springs 106 will yield if necessary, and the platen will change its angle if necessary, but in any event its welt-sustaining effect will be equalized as hereinbefore explained and the welt portion will have continuous backing around the toe and forepart to points behind the ball portion on each side of the shoe. It is not to be understood, however, that the invention is limited to any specific range of contact with the shoe, the foregoing description being based on a disclosure in which the range of contact is thus limited for a particular kind of work that need not be described. Obviously, in operating upon shoes of the stitchdown type, for example, it would be within the scope of the present invention to embody the platen in a form adapted to operate on the heel end of the shoe with or without one formed and arranged to operate on the toe end. Furthermore, it would be within the scope of the invention to extend one platen or the other to sustain the welt

portion throughout the shank of the shoe. These possible variations would not alter the fundamental principles involved in equalizing the pressure at the two sides of the shoe, nor those involved in the construction of the 5 platen whereby it is capable of being adjusted for different widths and for different lengths without interrupting the continuity of the welt-engaging surface.

Having thus described this invention, what 10 is claimed as new and is desired to secure by Letters Patent of the United States is:

1. In a machine for operating upon a lasted shoe, means arranged to apply pressure to 15 the bottom of the sole, and means arranged to co-act therewith to clamp the sole-extension at opposite sides of the shoe, one of said means being arranged to equalize the pressure at each side of the shoe relatively to that at the opposite side.

2. In a machine for operating upon a lasted shoe, a platen formed and arranged to sustain the welt at opposite sides of the shoe, and platen-supporting means arranged to 25 equalize the sustaining effect of the platen at each side of the shoe relatively to that at the opposite side.

3. In a machine for operating upon a lasted shoe, a substantially U-shaped platen arranged to sustain the welt around one end 30 and along opposite sides of the shoe, and platen-supporting means arranged to equalize the sustaining effect of the two branches of the platen at each side of the shoe relatively to that at the opposite side.

4. In a machine for operating upon a lasted shoe, platen elements arranged to sustain the welt at opposite sides of the shoe, and oscillatory means supporting said elements 40 and arranged to afford unitary movement of the latter to equalize the sustaining effect at each side of the shoe relatively to that at the opposite side.

5. In a machine for operating upon a lasted shoe, platen elements arranged to sustain the welt at opposite sides of the shoe, and platen-supporting means arranged to rock about an axis substantially coincident with the mean longitudinal line of said elements.

50 6. In a machine for operating upon a lasted shoe, a substantially U-shaped platen formed and arranged to sustain the welt around one end and along opposite sides of the shoe, and platen-supporting means arranged to rock about an axis substantially coincident with the mean longitudinal line of the platen.

7. In a machine for operating upon a lasted shoe, welt-sustaining means comprising 60 platen elements arranged to bear on the welt along the sides of the shoe, means connecting said platen elements, and means for supporting said connecting means, the platen elements and said connecting means being arranged to rock collectively relatively to said

supporting means about an axis substantially coincident with the longitudinal median line of the platen elements.

8. In a machine for operating upon a lasted shoe, welt-sustaining means comprising a 70 platen arranged to bear on the welt portion of the shoe, movable means for supporting the platen, and means for supporting said movable means, the latter being arranged to rock on an axis substantially coincident with 75 the longitudinal median line of the shoe bottom.

9. In a machine for operating upon a lasted shoe, platen elements formed and arranged to sustain the welt at opposite sides 80 of the shoe, and platen-supporting means comprising an oscillatory element arranged to equalize the sustaining effect of the platen elements at each side of the shoe relatively to that at the opposite side, said platen elements being movable laterally relatively to said oscillatory element to conform to the contour of the shoe.

10. In a machine for operating upon a lasted shoe, platen elements formed and arranged to sustain the welt around one end and along opposite sides of the shoe, said elements being pivotally connected together at the shoe-end portion and thereby adapted to swing toward and from each other, and 90 movable platen supporting means arranged to equalize the sustaining effect of the platen elements at each side of the shoe relatively to that at the opposite side.

11. In a machine for operating upon a lasted shoe, welt-sustaining means comprising oscillatory supporting means, a pair of platen-holders carried by said supporting means, and a pair of platen elements carried by said platen-holders respectively and arranged to sustain the welt at opposite sides of the shoe, said platen elements being capable of yielding relatively to said holders, said oscillatory supporting means being arranged to equalize the sustaining effect of 100 said platen elements at each side of the shoe relatively to that at the opposite side, and said holders being pivotally connected to said means to swing said platen elements toward and from each other. 110

12. In a machine for operating upon a lasted shoe, a substantially U-shaped platen formed and arranged to sustain the welt around one end and along opposite sides of the shoe, and platen-supporting means arranged to move to equalize the sustaining effect of the two branches of the platen at each side of the shoe relatively to that at the opposite side, said means including yielding means arranged to enable the platen to 120 yield bodily in addition to equalizing the sustaining effect as aforesaid.

13. In a machine for operating upon a lasted shoe, platen elements arranged to sustain the welt at opposite sides of the shoe, 130

- an oscillatory support, and yielding means connecting said platen elements with said support, the latter being arranged to equalize the sustaining effect of the platen elements at each side of the shoe relatively to that at the opposite side, and said yielding means being arranged to enable the platen elements to yield relatively to the support. 5
14. In a machine for operating upon a lasted shoe, platen elements arranged to sustain the welt at opposite sides of the shoe, and platen-sustaining means arranged to equalize the sustaining effect of said elements, said means being adjustable to position the platen according to the spring of the shoe in addition to affording the aforesaid equalizing effect. 10
15. In a machine for operating upon a lasted shoe, last-sustaining means, and means arranged to sustain the welt portion of the shoe independently of the last, said welt-sustaining means including platen elements arranged to bear on the welt along the sides of the shoe, and means for supporting the platen elements in operative position, said supporting means comprising adjusting elements arranged to adjust the platen to various inclinations according to the spring of the shoe and means arranged to equalize the 25 welt-sustaining effect of the platen elements. 30
16. In a machine for operating upon a lasted shoe, the combination with a tilting last-holder, of a platen arranged to sustain the welt, platen-sustaining means arranged to tilt the platen according to the longitudinal inclination of the welt, said means including adjustable connections arranged to maintain the platen at various angles of inclination, and a toe-rest arranged to operate with said last-holder to sustain the shoe, said toe-rest being adjustable to tilt the shoe about the axis of the last-holder independently of the platen and thereby to determine the longitudinal inclination of the 40 welt according to that of the platen. 45
17. In a machine for operating upon a lasted shoe, last-sustaining means having provisions for varying the longitudinal inclination of the shoe, pressure-applying means including a sole-engaging element and a carrier therefor arranged to tilt according to said inclination, and welt-sustaining means formed and arranged to sustain the welt at opposite sides of the shoe and to 50 equalize the sustaining effect at each side relatively to the other. 55
18. In a machine for operating upon a lasted shoe, welt-sustaining means comprising platen elements each comprising sections arranged to bear on the welt at opposite sides of the shoe, means for adjusting the sections with respect to one another in the general direction of the length of the shoe, said elements being movable toward and 60 from each other, and a plurality of yielding 65 means arranged normally to hold said elements against the body of the shoe. 70
19. In a machine for operating upon a lasted shoe, welt-sustaining means comprising platen elements arranged to bear on the welt at opposite sides of the shoe, a platen-holder including relatively movable sections, yielding means connecting the platen elements with said sections, and yielding means arranged to act on said sections to keep the platen elements normally against the body of the shoe. 75
20. In a machine for operating upon a lasted shoe, welt-sustaining means comprising a substantially U-shaped platen formed and arranged to bear on the welt around one end and along opposite sides of the shoe, said platen including relatively movable sections pivotally connected to each other to form a hinge-joint, and a platen-holder consisting of relatively movable sections pivotally connected to each other to form a hinge-joint, said hinge-joint being co-axial. 80
21. In a machine for operating upon a lasted shoe, welt-sustaining means comprising a series of platen members arranged to bear on the welt, said members being jointed one to another so as to be capable of relative movement and having lapped welt-engaging portions in contiguous and flush relation to each other. 85
22. In a machine for operating upon a lasted shoe, welt-sustaining means comprising a series of platen members arranged to bear on the welt, two of said members being pivotally jointed to each other so as to be capable of relative angular movement and having lapped welt-engaging portions in contiguous and flush relation to each other. 90
23. In a machine for operating upon a lasted shoe, welt-sustaining means comprising a series of platen members arranged to bear on the welt, two of said members having co-operative joint-forming portions in contiguous relation to each other and being capable of relative bodily movement, said portions being lapped and having flush welt-sustaining surfaces. 95
24. In a machine for operating upon a lasted shoe, welt-sustaining means comprising pivotally jointed platen members arranged to sustain the welt around an end of the shoe, and platen members arranged to sustain the welt along the sides of the shoe, the side platen members being jointed respectively with the end platen members and being adjustable lengthwise relatively thereto, the contiguous portions of all said members being lapped one with another and having welt-sustaining surfaces in flush relation to each other. 100
25. In a machine for operating upon a lasted shoe, welt-sustaining means comprising pivotally connected platen members 105
- 110
- 115
- 120
- 125
- 130

mortised one into another and having lapped welt-engaging portions in flush and contiguous relation to each other.

26. In a machine for operating upon a lasted shoe, welt-sustaining means comprising platen members mortised one into another so as to be capable of relative lengthwise movement, and having lapped welt-engaging portions in flush and contiguous relation to each other.

27. In a machine for operating upon a lasted shoe, welt-sustaining means comprising a platen member having a curved welt-sustaining edge, and a platen member having a welt-sustaining edge occupying tangential relation to said curved edge, said members being capable of relative movement while maintaining such tangential relation of said edges.

28. In a machine for operating upon a lasted shoe, welt-sustaining means comprising platen members pivotally connected to each other and arranged to sustain the welt around an end of the shoe, said members having welt-sustaining edges arranged in tangential relation to each other, and platen members arranged to sustain the welt along the sides of the shoe, the side platen members being jointed with the end platen members respectively so as to be capable of endwise movement relatively thereto and having welt-sustaining edges occupying tangential relation to those of the end platen members.

29. In a machine for operating upon a lasted shoe, welt-sustaining means comprising platen members mortised one into another so as to be capable of relative lengthwise movement, and spring-pressed friction means arranged to hold said members in various relations but adapted to slip as one member is moved relatively to the other.

30. In a machine for operating upon a lasted shoe, welt-sustaining means comprising platen members arranged to sustain the welt at the sides, respectively, of the shoe, said members being adjustable relatively to each other, and a single adjusting means connected to said members and arranged to execute movement of one kind to adjust said members relatively, one to the other, and to execute movement of another kind to adjust them collectively.

31. In a machine for operating upon a lasted shoe, welt-sustaining means comprising platen members arranged to sustain the welt at the sides, respectively, of the shoe, said members being adjustable lengthwise of the shoe, and a single adjusting means connected to said members and arranged to execute one kind of movement to adjust said members lengthwise in a common direction, and to execute another kind of movement to adjust them in opposite directions.

32. In a machine for operating upon a

lasted shoe, welt-sustaining means comprising platen members arranged to sustain the welt at the sides, respectively, of the shoe, and means connected to said members to adjust them, said means being arranged to execute angular movement to adjust the platen members in opposite directions, and to execute bodily movement to adjust the platen members in a common direction.

33. In a machine for operating upon a lasted shoe, welt-sustaining means comprising platen members arranged to sustain the welt at the sides, respectively, of the shoe, and an adjusting member having pivotal connection with each of said platen members, said adjusting member being arranged to execute angular movement to adjust one of said platen members relatively to the other, and to execute bodily movement to adjust the platen members collectively.

34. In a machine for operating upon a lasted shoe, welt-sustaining means comprising platen members arranged to sustain the welt at the sides, respectively, of the shoe, means to support said platen members so as to afford movement of each relatively to the other, and an adjusting member carried by said platen members conjointly and pivotally connected to each, said adjusting member being capable of different kinds of movement to adjust said platen members collectively or individually.

35. In a machine for operating upon a lasted shoe, welt-sustaining means comprising platen members arranged to sustain the welt along the sides, respectively, of the forepart of the shoe, the rear portions of said members being curved to conform to the ball portion, and welt-engaging means formed and arranged to bear on the welt around the toe end of the shoe, said platen members being adjustable with respect to one another lengthwise of the shoe and being jointed with said welt-engaging means so as to maintain a flush and continuous welt-sustaining surface around the end of the forepart.

36. In a machine for operating upon a lasted shoe, welt-sustaining means comprising a series of platen members mortised one into another and having contiguous welt-engaging portions in flush relation to each other, said members, collectively, forming a continuous welt-sustaining surface conforming to both sides of the forepart from the toe end to points at the rear of the ball portion, and being adjustable relatively to one another lengthwise of the shoe to various sizes while maintaining the contiguity and the flush relation of their welt-engaging portions.

37. In a machine for operating upon a lasted shoe, welt-sustaining means comprising platen members formed and arranged to sustain the welt around an end of the shoe and having joint-forming portions mortised

one into another, said members being adjustable relatively to each other for shoes of different widths, and platen members arranged to sustain the welt along the sides of the shoe and having curved portions conforming to the side contour of the shoe, the side platen members and the end platen members having coöperative joint-forming portions mortised one into another and being relatively adjustable to suit shoes of different lengths, said joint-forming portions

having coöperative welt-sustaining surfaces in contiguous and flush relation to each other and being formed and arranged to maintain such relation in the various width and length relations of the several platen members. 15

In testimony whereof I have signed my name to this specification.

EDWARD L. BROCK,
Administrator of the estate of Matthias Brock.
